UNITED STATES PATENT OFFICE

167,292

COMBINED VEGETABLE DISH AND LID

Franz Wagner, Chicago, Ill., assignor to Easterling
China Company, Chicago, Ill., a corporation of Illinois

Application October 30, 1951, Serial No. 17,172

Term of patent 3½ years

(Cl. D44—15)

To all whom it may concern:

Be it known that I, Franz Wagner, a citizen of the United States, residing at Chicago, county of Cook, and State of Illinois, have invented a new, original, and ornamental Design for a Combined Vegetable Dish and Lid, of which the following is a specification, reference being had to the accompanying drawing, forming a part hereof.

I claim:

The ornamental design for a combined vegetable dish and lid, as shown.

FRANZ WAGNER.
